Primary Examiner — Cynthia Ramirez(74) *Attorney, Agent, or Firm* — Sughrue Mion, PLLC(57) **CLAIM**

The ornamental design for a cart, as shown and described.

DESCRIPTION

FIG. 1 is a perspective view of a cart showing my new design; FIG. 2 is a front elevation view thereof.

FIG. 3 is a rear elevation view thereof.

FIG. 4 is a right side elevation view thereof.

FIG. 5 is a left side elevation view thereof.

FIG. 6 is a top plan view thereof.

FIG. 7 is a bottom plan view thereof.

FIG. 8 is a sectional view of line 8-8 in FIG. 2.

FIG. 9 is a sectional view of line 9-9 in FIG. 2.

FIG. 10 is a right side elevation view thereof showing the top board heightened; and,

FIG. 11 is a referential view showing use thereof.

The portion of the cart shown in broken lines is for the purpose of showing environmental structure only and forms no part of the claimed design.
